UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP CONSISTING OF FRANCIS E. MYERS AND PHILIP A. MYERS.

PUMP.

1,244,534.

Specification of Letters Patent. Patented Oct. 30, 1917.

Application filed November 4, 1916. Serial No. 129,415.

To all whom it may concern:

Be it known that I, PHILIP A. MYERS, a citizen of the United States, residing at Ashland, in the county of Ashland and State of Ohio, have invented certain new and useful Improvements in Pumps, of which the following is a specification, reference being had therein to the accompanying drawing.

10 This invention relates to pumps. The object of the present invention is to provide a construction which will require very little attention and in which friction and resistance are reduced to a minimum. To achieve 15 this object it is my intention to arrange the working head with reference to the pump so that resistance and frictional engagement between the relatively moving parts are reduced to a minimum; to reduce 20 the number of relatively moving parts as far as possible and to provide a suitable system of lubrication for such relatively moving parts as are necessary to the proper operation of the mechanism.

25 In the accompanying drawings, Figure 1 is an elevation illustrating one embodiment of the invention in which the cross head is driven by means of an eccentric; Fig. 2 is a similar elevation looking toward the right 30 of Fig. 1; Fig. 3 is an elevation illustrating a slightly modified form in which a crank is used for operating and reciprocating the cross head; and Fig. 4 is a detail view of one of the side arms showing a spring attached thereto which serves to balance the 35 pump and even up the momentum.

The mechanism herein illustrated shows the working head arranged for well work beyond the limit of suction. The working 40 head also has a straight stroke adaptable for either single or double acting cylinders as may be required. The mechanism herein shown, however, is for the purpose of illustration only.

45 Referring to Figs. 1 and 2, 1 indicates the discharge head of the pump provided with a suitable orifice 2, a packing gland 3 and a reciprocating piston rod 4. The pump is provided with a suitable ledge or support 50 5 for supporting the working head 6 which comprises the mechanism for reciprocating the piston rod. The working head is adjustable upon the ledge 5 and is provided with suitable legs 7 and feet 8 resting upon 55 the said ledge. This adjustability allows

the working head to be located in proper position with reference to the pump so that the side thrust upon the piston rod can be reduced to a minimum, thereby preventing friction and wear. Supported by the legs 60 7 is a sectional casing comprising a lower section 9 adapted to receive oil or other lubricating substance and an upper section 10 comprising the cylindrical upper portion 11 and attached to the lower section, as indicated at 12. The assembled casing has journaled therein a gear 13 which is driven by means of the pinion 14 also located within the casing. The pinion and gear are rotated from any suitable source of power 70 through the pulley 15. Attached to the gear 13 is an eccentric 16 provided with an arm 17 attached to the slide 18 forming a part of the cross head. This slide reciprocates within the cylindrical portion of the upper 75 section of the casing and the whole working head is so mounted with reference to the pump that this slide is substantially in alignment with the piston rod and reciprocates back and forth in the same direction therewith and in alignment therewith. By the above arrangement the resistance and friction is practically eliminated because contact between the points is avoided. Fixed 80 to the slide is the transversely extending member 19 of the cross head which reciprocates within the slots 20 arranged on opposite sides of the cylindrical sectional portion of the casing. At each side of the casing 85 is a side arm 21. These arms are connected at their lower ends to a cross piece 22 fixed at 23 to the piston rod and at their upper ends to the member 19. The side arms 21 reciprocate in a vertical line only and have no radial movement around axes. It is, 90 therefore, unnecessary to lubricate these parts to reduce the friction.

In order to lubricate the slide 18 and associated parts, such as the eccentric arm, etc., I have provided a suitable pump 24 which serves to pump oil from the lower section of the casing through a conduit 25 to a point above the slide, whereby these parts are properly lubricated. This pump 100 may also be utilized, if desired, to feed oil to a point above the shaft supporting the gear wheel 13. Any suitable device may be used for actuating the pump and any suitable pump may be used. In the present instance I have shown an eccentric 26 con- 105 110

nected to the pump and operated by the transmission mechanism within the casing. By the above construction it will be seen that I have produced a working head in 5 which the relatively movable parts are all lubricated by suitable oiling devices. It is to be understood that the piston rod is naturally water lubricated and needs no special oiling devices. The arrangement of the 10 working head with reference thereto, however, is such that there will be very little rubbing between the relatively movable parts.

The specific means for transferring the 15 power from the transmission devices within the casing to the slide may be varied. In Figs. 1 and 2 for the purposes of illustration I have shown an eccentric and arm connected thereto. In Fig. 3 I have illustrated a 20 form in which a crank 27 connected by a connecting rod 28 to the slide is utilized for transferring this power from the gear 13 to the slide.

In Fig. 4 I have illustrated a detail which 25 may be easily applied to the side arms illustrated in the construction shown in Figs. 1, 2 and 3. Referring to Fig. 4 the side arm may be indicated by the numeral 29. This arm reciprocates through an apertured abut- 30 ment 30 and is provided at the upper portion thereof with an adjustable collar 31. Interposed between the abutment which is attached to any suitable part of the fixed frame and the adjustable collar is a com- 35 pression spring 32. A spring of a similar nature is applied to the arms at each side. The function of the above device is to balance the pump and even up the momentum thereof.

40 While I have shown and described one embodiment of the invention it will be understood that the same has been chosen for the purposes of illustration only, and that I do not desire to be limited to the details 45 of construction shown and described.

Having thus fully described my invention, what I claim as new and desire to secure by Letters Patent, is:—

1. In a pump, the combination, with a dis- 50 charge head and a piston rod passing through said head, and guided thereby, of a base plate supporting said head, a frame comprising legs carried by said plate, said frame having integral therewith a semi- 55 cylindrical casing, transmission devices comprising actuating gearing journaled in said casing, a second semi-cylindrical casing above and fast to the first casing, said sec-

ond casing having an upwardly extending portion integral therewith, a cross head 60 guided in said extended portion and thereby kept rigidly in line with said piston rod, means outside said casing for connecting said piston rod to said cross head, an oil pump in the lower part of said first casing, 65 and a pipe leading from said pump to a point above said cross head, and thus lubricating said cross head and said transmission gearing by the gravity of the oil.

2. In a pump, the combination, with a 70 piston rod, and a plate serving to guide the same, of a gear casing, semi-cylindrical in shape, having an imperforate bottom with legs integral therewith and fast to said plate, said casing serving to hold a supply of 75 lubricating oil, transmission gearing mounted in said casing, a second casing, also semi-cylindrical in shape, closely fitting said first casing and having a vertically extending cylindrical portion, a cross head mounted 80 in said cylindrical portion, and connected to both said transmission gearing and said piston rod, and an oil pump in said first casing, having connections to pump oil from the oil supply in said casing, and to elevate 85 said oil and to discharge it in said cylindrical portion above said cross head, thus lubricating said cross head and gearing by the gravity of the oil.

3. In a pump, the combination, with a 90 gear casing having an imperforate bottom serving to retain an oil supply, transmission gearing mounted in said casing, a cross head mounted in said casing directly over and driven by said gearing, a pump piston rod 95 directly under said casing and having connections to said cross head outside said casing, and an oil pump in said casing having connections to elevate oil from said supply and to discharge it in said casing above said 100 cross head, thus lubricating said cross head and gearing by the gravity of the oil.

4. In a pump, the combination, with a 105 casing having an imperforate bottom serving to retain an oil supply, transmission gearing in said casing, a cross head mounted in said casing directly over and having connections to said transmission gearing, and an oil pump mounted in said casing and having connections to elevate oil from said 110 oil supply and to discharge it in the upper part of said casing above said cross head, thus lubricating said cross head and said gearing by the gravity of the oil.

In testimony whereof, I affix my signature. 115
PHILIP A. MYERS.
